THE NORRIS PETERS CO., PHOTO-LITHO., WASHINGTON, D. C.

UNITED STATES PATENT OFFICE.

LOUIS LOEB, JR., OF RORSCHACH, SWITZERLAND.

EMBROIDERED FLOUNCED FABRIC.

SPECIFICATION forming part of Letters Patent No. 430,347, dated June 17, 1890.

Application filed August 1, 1889. Serial No. 319,387. (No specimens.)

To all whom it may concern:

Be it known that I, LOUIS LOEB, Jr., a subject of the Emperor of Germany, residing at Rorschach, Switzerland, have invented a new and Improved Embroidered Flounced Fabric, of which the following is a full, clear, and exact description.

My invention relates to an embroidered flounced fabric intended for use more particularly in garments for ladies' or children's wear, and made as muslins, cambrics, woolens, silks, &c.; and the object of the invention is to provide an improved fabric of this class as a new article of manufacture, having one or more flounces formed with an embroidered free edge and capable of production in any desired form or pattern without requiring the main piece of material to be made longer or wider than the finished flounced fabric, while the flounces will be safe against detachment or ripping off by wear or washing of the fabric.

The invention consists in certain features of novelty in the embroidered flounced fabric, as hereinafter described and claimed.

Reference is to be had to the accompanying drawings, forming a part of this specification, in which similar letters of reference indicate corresponding parts in all the figures.

Figure 1 is a front view of a piece of main fabric with a backing fabric laid behind it, the front or main fabric being embroidered in a manner necessary to produce series of flounces of various forms or patterns after the two materials or fabrics are connected together, preferably by embroidery-stitches, and the front material is partly cut away. Fig. 2 is a front view of the two fabrics connected by stitches or lines of embroidery, with the front material partly cut away or removed to allow the flounces to hang free from their main lines of connection. Fig. 3 is a back view of the finished flounced fabric. Fig. 4 is a cross-section of the main and backing fabrics, taken on the line *xx* in Fig. 1, or before they are connected. Fig. 5 is a cross-section of the finished flounced fabric taken on the line *yy* in Fig. 2. Fig. 6 is a front view of an embroidered flounced fabric, in which the lines of embroidery-stitches produced between two opposing lines of flounces

form a pocket between the two materials of the finished fabric to receive a colored ribbon—for instance, to display to better advantage the open-work embroidered patterns on the front material forming one side of said pocket; and Fig. 7 is a detail sectional view illustrating how the flounce may by the use of two or more backing-pieces be made of two or more thicknesses to give it increased body or stiffness.

My improved embroidered flounced fabric consists of a main fabric A and a backing or foundation piece or fabric B, connected thereto in a peculiar manner and preferably by embroidery-strokes, the front material being cut away between certain lines of embroidery on one fabric and certain lines of embroidery connecting the two fabrics to allow the finished embroidered flounce to hang or project, as hereinafter more fully explained.

The main fabric A, on which flounces of straight, angular, round, or other general form may be produced, is or may be left entirely plain where the flounces are not formed, or the main fabric may be embroidered at a above or below the flounce or series of flounces. The backing pieces or strips B, of which there may be any desired number having any required width, are placed behind the main fabric. Onto the main fabric A are worked one or more lines of embroidery of any required contour, extent, or direction, and this embroidery makes a finish at the free edges of the flounces of the completed fabric. For instance, the finely-scalloped line of embroidery *c* afterward forms the lower free edge of the flounce C of the finished fabric, the angularly-disposed lines of embroidery *d*, worked below the embroidery *c*, afterward form the marginal free edges of the series of angular-inclined flounces D, the finely-scalloped line of embroidery *e* afterward forms the free edge of the wide straight-face embroidered flounce E, the circular-scalloped lines of embroidery *f* afterward form the marginal free edges of the series of circular flounces F, and the wavy lines of embroidery *g* afterward form the free edges of a series of large scalloped flounces G of the completed fabric.

Whether the main fabric A be embroidered at *a* or be left plain where the flounces are

not to be produced on it, those portions of said fabric may be embroidered at places afterward within the marginal edges of the flounces, or between said edges and the lines or places 5 of connection whence the flounce hangs or projects. For instance, a series of dots d' are worked next the embroidery d , a complete flower-pattern e' is worked next the embroidery e , and a series of dots g' are worked next 10 the embroidery g . Embroidery-patterns may also be worked on the main fabric at the center of flounces, of round or square or oval configuration, as instanced by the flower or leaf pattern f' , worked at the center of the circular lines or figures of embroidery f . It will be understood that all the above-named lines 15 of embroidery c , d , d' , e , e' , f , f' , and g , g' , and also the embroidery a , when desired, are worked on or in the main fabric A before the 20 backing fabric B is connected to it by lines of stitches, and preferably by embroidering the two fabrics A B together. These lines or places of connection of the two fabrics A B vary in configuration as the patterns or general forms of the flounces or their embroidery 25 require. For instance, the zigzag or sharp wavy embroidery-line of connection C', produced through the two fabrics A B, forms the line of connection of the finished flounce C, 30 the angular lines of embroidery D' form the lines of connection of the flounces D, the straight horizontal line of embroidery E' forms the main line of connection of the wide straight flounce E, the rings of embroidery F' form 35 the lines of connection of the circular flounces F, and the concaved scalloped embroidery G' forms the line of connection of the series of connected or larger scalloped flounces G. Opposite the line of connection C' and next 40 the line of embroidery c the two fabrics A B are connected together, preferably by a line of embroidery C², which, because of the conformation of the flounces D, also opposes the lines of connection D' of said flounces. About 45 parallel with the line of connection E', above mentioned, the two fabrics are also connected or stitched together, and preferably by a line of embroidery E², which ranges along near the line of embroidery e and faces the embroidery f of the circular patterns, and also faces the line of connection G' of the complete flounces G, and below these flounces or their edge embroidery g the two fabrics A B are also connected, preferably by a line G² of 50 embroidery-strokes. An ornamental flower-pattern e^2 is also worked or embroidered through the two fabrics between the patterns e' and the embroidered line of connection E' of the flounce E, and between the zigzag line 55 of connection C' and the line of embroidery c, and preferably within the angles or convolutions of said connection C' small flower or other patterns c^2 are worked through both fabrics A B.

60 65 Figure 1 of the drawings shows all the embroidery patterns or lines produced simultaneously by a machine upon the main fabric

A, while Fig. 3, which is a back view, shows all the lines of connection of the two fabrics A B, which are made simultaneously in a machine; hence the production of my embroidered flounced fabric requires two adjustments of it in embroidering-machines, and the second operation is that which connects the two materials of which the flounced fabric is 75 made.

To complete the fabric it is only necessary to cut away or remove the front material A between the lines of embroidery which form the free edge of the flounce and the adjacent 80 line of connection of the two fabrics and between said lines of connection where they face each other. This is done preferably by using suitable scissors, which may be introduced between the two fabrics A B at such 85 places a' . Fig. 2 represents this fabric partly cut away at the right-hand side, while the remaining removable part a' at the left-hand side is slit off closely to the free embroidered edges of the tucks and the lines of embroidery connecting the two materials. This unremoved portion a' of the front main fabric A is represented by horizontal shading lines. Those end portions b^2 of the backing B which extend beyond the embroidered lines of connection C' C² of the flounced fabric are 90 preferably cut away at the back of the fabric, and as will be understood from Fig. 3 of the drawings, which shows the free ends b^2 of the backing cut away at the right-hand and 95 remaining at the left-hand side of said figure.

From the aforesaid description it will appear that my improved flounced fabric has a flounce, which is formed of a part of the main fabric, and is provided with an embroidered 100 free edge, and that the flounce is held to the backing of the finished fabric by embroidery-strokes forming their own complete smooth selvage or line of connection, which will not rip or fray out, and that the flounce may be 110 embroidered at its face between its free edge and main line of connection and through one or both pieces A B of material, and that the backing B is not only the main support to the 115 series of flounces, but it maintains the lengthwise continuity of the whole fabric, which when flounced has the same length the main fabric had before the flounces were formed.

It will be particularly noticed that the flounce or flounces of the finished fabric are 120 formed of parts of the front fabric occupying their original woven positions, or those facial positions relatively to the remaining or unflounced parts of the front fabric which they had when this fabric was first woven or produced. This feature alone makes the flounced fabric as an article of manufacture clearly distinguishable from ordinary flounced fabrics, as ordinary observers, as well as experts, will see that in my improved flounced fabric 125 the warp and woof threads of all the flounces have the same direction as the warp and woof threads of the remaining unflounced portions of the main front fabric, however 130

irregular the marginal design of the flounces may be, and this clearly identifies the flounces as being formed of parts of the front fabric occupying their original facial woven positions. It will also be seen that all flounces of like general form in an improved fabric have almost absolute uniformity of design, however irregular marginally this design may be, and the spacing of like flounces is or may 10 be absolutely regular or uniform. These two desirable features it is almost impossible, or, at least, impracticable, with commercial success, to assure in either a hand or machine made flounced fabric having very irregularly-shaped flounces separately formed and afterward attached to a backing or foundation piece; and, finally, my improved flounced fabric presents a more symmetrical and smooth and more easily laundered face than would a 15 flounced fabric having flounces of like form, as in my fabric, but which have been separately or individually made and afterward attached to a backing or foundation fabric.

I specially mention the connection of the 20 flounce by embroidering the two pieces of material together at the place from which the flounce hangs or projects, as by this construction I produce a very ornamental finished fabric at a trifling cost in comparison with the 25 expense attending the production of a fabric of the same design by applying the flounces as separate pieces to the main fabric. For instance, it would be very difficult and commercially impracticable with profit to form 30 flounces, like the ones C D F G, by using independent pieces of material cut out to proper shape and turned in at the edges in zigzag, curved, or rounded lines, where they would be stitched to a supporting-fabric, and it 35 would be quite impossible to secure regularly-spaced flounces of precisely the same pattern, which is required to make a beautiful useful fabric of this class. I also specially state that a flounced fabric in which the 40 flounce is formed of a part of the main fabric and is held to it or to the backing by a line of embroidery is a much more smoothly-finished fabric than one in which the flounce is formed of a separate piece stitched to the 45 main fabric, because in my fabric there never is a loose or free edge at the embroidered line of connection of the flounce, which forms its own selvage; hence the fabric presents a perfectly-smooth and beautiful finish at the place 50 from which the flounce hangs or projects, and this place or line of connection may have any contour or direction within the capacity of an embroidering-machine.

I briefly state that Fig. 6 of the drawings 55 shows how two opposing flounces H H may be produced on the finished fabric, so as to project from embroidered lines of connection H' H' of the two materials A B and the embroidered lines of connection H² H², which are 60 next the embroidered free edges h h of the flounces, form a pocket between the two materials A B to receive a ribbon I of any pre-

ferred color, which will display to advantage the fancy open-work-embroidery patterns i, which were first worked onto the front or 70 main fabric A. Between the line of connection H' of the lower flounce H and another lower line of connection J² of the two fabrics A B are produced reversely-inclined rows of diagonal flounces J J, which have free edges 75 j of embroidery, and hang or project from embroidered lines of connection J' of the two fabrics or materials. The flower-patterns j' on the flounces are first embroidered on the outer main fabric A, as are also the patterns 80 a² at the upper and lower angles of the flounces, or between them and the lines of connection H' J² of the two materials. The flower-patterns a³ are embroidered through the two materials A B next the tops or connected edges of the flounces. I specially mention this flounced fabric made with two opposing flounces, as H H, and two embroidered lines of connection, as H² H², which may be straight or irregular, and which form a pocket 90 to receive a ribbon to display effectively embroidered patterns worked only through the front material forming the outer wall of the pocket.

When the finished flounces are to have two 95 or more thicknesses of material, two thicknesses, for instance, as shown in Fig. 7 of the drawings, I connect an extra backing B' directly to the main fabric A by a line of embroidery-strokes k, which forms the free edge 100 of the double-thick flounce, and then I connect the main backing B at the back of the piece B' and by two lines of embroidery-strokes k' k', passed through all the fabrics or materials, and the front materials A B', or 105 all the fabrics except the back piece B, are then cut away at k', between the first line of embroidery k and the adjacent line of connection k' of all the fabrics.

Having thus described my invention, what 110 I claim as new, and desire to secure by Letters Patent, is—

1. As an improved article of manufacture, a flounced fabric comprising a main face or front fabric and a connected backing fabric 115 and having one or more flounces formed of parts of the front fabric occupying facially their original woven positions relatively to the remaining portions of said front fabric, substantially as herein set forth.

2. As an improved article of manufacture, a flounced fabric comprising a main face or front fabric and a connected backing fabric and having one or more flounces formed of parts of the front fabric occupying facially 125 their original woven positions relatively to the remaining portions of said front fabric and provided with an embroidered free edge, substantially as herein set forth.

3. As an improved article of manufacture, 130 a flounced fabric comprising a main face or front fabric and a connected backing fabric and having one or more flounces formed of parts of the front fabric occupying facially

their original woven positions relatively to the remaining portions of said front fabric and provided with an embroidered free edge, and also having embroidered patterns between their free edge and their line of connection, substantially as herein set forth.

4. As an improved article of manufacture, an embroidered flounced fabric comprising a main face or front fabric and a backing fabric and having one or more flounces formed of parts of the front fabric occupying facially

their original woven positions relatively to the remaining portions of said front fabric and provided with an embroidered free edge and hanging or projecting from lines of embroidery connecting both fabrics, substantially as herein set forth. 15
